UNITED STATES PATENT OFFICE.

LIONEL NORMAN, OF WINCHESTER, MASSACHUSETTS.

PAPER PAIL.

1,119,981.

Specification of Letters Patent.

Patented Dec. 8, 1914.

Application filed February 14, 1913. Serial No. 748,337.

To all whom it may concern:

Be it known that I, LIONEL NORMAN, a citizen of the United States, residing at Winchester, in the county of Middlesex and State of Massachusetts, have invented certain new and useful Improvements in Paper Pails; and I do hereby declare the following to be a full, clear, and exact description of the invention, such as will enable others skilled in the art to which it appertains to make and use the same.

The invention relates to paper pails for storing or shipping edible or other products, and more particularly to that class of pails provided with fastening devices for securing a cover to the pail.

The object of the present invention is to provide a pail of this character with a cover fastening device which may be readily applied to the pail in such manner that under all conditions of use sufficient pressure to form a strong joint will be maintained between the cover and the pail.

To this end the invention contemplates the provision in a pail provided with a cover, removable to permit access to the interior of the pail, of a fastening device for holding the cover against movement provided with a portion formed for penetration into the material of the cover and another portion constructed for locking engagement with a part of the pail, the arrangement being such that as the fastening device is assembled in position the pressure necessary to embed the penetrating portion in the cover forces the cover on the pail, and the joint so formed is maintained by the other portion of the fastening device when it springs into locking engagement with the pail part at a time when the cover and pail are still under pressure.

The various features of the present invention will be readily understood from an inspection of the accompanying drawings,

in which—

Figure 1 is a sectional elevation of a pail embodying the invention; Fig. 2 is a plan view of the blank of resilient metal from which the pail fastening member is formed; Fig. 3 is a sectional elevation on the line 3—3, Fig. 4, of the completed pail fastening member; Fig. 4 is a side elevation, and Fig. 5 a plan view of the pail fastening member; Fig. 6 is a plan view, and Fig. 7 a side elevation of the cover fastening member before the upper portion thereof

is bent in final shape; and Fig. 8 is a detail elevation showing the completed cover fastening member.

In the construction shown in the drawings, the pail 1 is a cylindrical receptacle for storing or shipping butter, etc., and is provided with a cover 2 having a marginal flange 3, one wall of which fits tightly the interior of the pail, and the other wall of which rests on the top of the pail. The cover is removable to permit access to the interior of the pail, and a pair of fastening devices are provided on opposite sides of the pail for securing the cover in position on the pail, one member of each pair being clenched to the pail and the other member of each pair being connected to the cover. The pail fastening member is formed from a blank 4 of resilient sheet metal comprising a body portion 5 terminating in bosses 6, and an intermediate portion forming a blank 7 for a bail hook to be described. The pail fastening member is shaped out of the blank 4 by upsetting the body portion 5 to form the spacing pieces 8 and shoulders 9 thereby converting the body portion into an arch 10 bridging the end bosses 6. Projecting in opposite directions from the bosses 6 are narrow, tapered strips 11 which are bent down parallel to each other in a direction at right angles to the bosses 6 to form tangs which may be clenched through the material of the pail to secure the pail fastening member in position as shown in Fig. 1. When in position, the ends of the fastening member are flush with the pail, the portion bridging the ends being spaced from the pail by the pieces 8 to form a central opening for the reception of the cover fastening member. The cover fastening member is formed from a strip of resilient sheet metal comprising the body portion 12, one end of which is provided with a pair of separated pointed fingers 13, and the other end of which is provided with a tapered spring tongue 14. The tongue 14 terminates at one end in a shoulder 15 connecting the tongue with the body portion 12 and at the other end in a rounded nose 16 bent at an angle to the tongue. The fingers 13 are bent at right angles to the body portion 12 and the body portion is also bent intermediate its ends to form the completed cover fastening member illustrated in Fig. 8. The pail fastening member is secured to the side of the pail with the

lower edge of the bridge 10 located at a distance from the top of the pail equal to the distance from the shoulder 15 to the bend 17 in the cover fastening member for a purpose which will presently be described.

- In assembling the cover fastening member the pointed fingers 13 are directed at the cover and the rounded nose 16 at the central opening beneath the bridge 10.
- 10 When the fingers reach the cover sufficient pressure is brought to bear upon the fastening to embed the fingers in the material of the cover. This pressure causes the cover to be forced on the pail and the tongue to slide beneath the bridge 10. The tongue and bridge yield to permit the passage of the tongue until the shoulder 15 is reached when the resiliency of the tongue and bridge causes the shoulder to spring into locking engagement with the lower edge of the bridge 10. As the distance from the lower edge of the bridge to the top of the pail is equal to the distance from the shoulder 15 to the bend 17 in the cover fastening member, the springing of the shoulder into locking engagement with the bridge occurs simultaneously with the embedment of the fingers 13 into the material of the cover and at a time when the cover and pail are being pressed together. As the parts of the fastening device are made of stiff resilient metal substantially inflexible under the ordinary conditions occurring in the use of the pail, the pressure between the cover and pail imparted during the penetration of the cover is retained, resulting in a tight joint between the cover and pail sufficiently strong to withstand the jolts of shipping and handling.
- 40 To facilitate the handling of the pail, a bail 18 is provided which is looped across the pail and secured at opposite sides of the pail to hooks 19 shaped to the form shown in Fig. 4 from the blank 7 carried by the pail fastening members. It is desirable that the bail remain either in an upright position where it may be readily grasped to move the pail, or down against the sides of the pail, and to this end the shoulders 9 on the bridge 45 are arranged so that the bail is wedged between the shoulders and the hook when

the bail is elevated or down against the sides of the pail.

Having explained the nature and object of the invention, and specifically described 55 one form of pail in which it may be embodied, what I claim is:—

1. A pail, having, in combination, a cover, and a fastening device for holding the cover against movement, comprising a portion 60 constructed for embedment in the cover, and another portion constructed for locking engagement with the pail, said portions being so arranged that the movement of the penetrating portion of the fastener into the cover 65 brings the locking portion into locking engagement with the pail.

2. A pail, having, in combination, a cover, and a fastening device for holding the cover against movement, one member of which is 70 formed of a single integral blank comprising end portions secured to the pail and an arched portion bridging the ends, the other member of which is formed of a strip of resilient material, having a portion formed 75 for connection to the cover, and another portion formed for locking engagement with the bridge, said portions being arranged to become connected and locked simultaneously when assembled in cover holding 80 position.

3. A pail, having in combination, a cover, and a locking device for holding the cover against movement, one member of which is formed of a single integral blank comprising 85 end portions secured to the pail and an arched portion bridging the ends, the other member of which is formed of a strip of resilient material having one portion formed for penetration into the material of the 90 cover, and another portion formed as a spring tongue terminating in a shoulder shaped for locking engagement with the bridge of the other member, said portions being so arranged that complete penetration 95 into the material of the cover occurs simultaneously with the springing of the shoulder into locking engagement with the bridge.

LIONEL NORMAN.
